UNITED STATES PATENT OFFICE.

JONAS M. HARMONY, OF CANTON, OHIO, ASSIGNOR OF ONE-HALF TO DAVID H. JACKSON, OF SAME PLACE.

BOTTLE-STOPPER.

SPECIFICATION forming part of Letters Patent No. 659,895, dated October 9, 1900.

Application filed June 15, 1900. Serial No. 20,388. (No model.)

To all whom it may concern:

Be it known that I, JONAS M. HARMONY, a citizen of the United States, residing at Canton, in the county of Stark and State of Ohio, have invented a new and useful Bottle-Stopper, of which the following is a specification.

My invention relates to a device for preventing the refilling of bottles or other packages for fluids or liquids, and has for its object to accomplish this without interfering with pouring from or emptying such bottle or package whenever desired. I attain this by the mechanism illustrated in the accompanying drawings, in which—

15 Figure 1 is a longitudinal section of the neck of a bottle with an ordinary cork, showing the stopper partly in section therein on the line xx , Fig. 2; Fig. 2, a longitudinal section of the neck of a bottle tilted or inverted 20 with the cork removed and of the stopper therein on the line yy , Fig. 1; Fig. 3, a detached isometric view of one-half of the stopper-case; Fig. 4, a detached isometric view of the valve-seat, and Fig. 5 a detached isometric view of the valve.

Similar numerals refer to similar parts throughout the several views.

The case 1 of the stopper is made, preferably, of glass and in two similar lateral halves, 30 one of which is illustrated in Fig. 3. The case as a whole is circular in section, with the diameter of the outer end slightly larger than the diameter of the inner end, thus making the longitudinal section slightly wedge-shaped. Within the lower or inner part of the case 1 is formed the recess or cavity 2, the lower portion of which is somewhat constricted, forming the shoulder 3. Within and near the lower opening of the cavity 2 is provided the annular groove 4, adapted to receive the annular bead 5 around the lower part of the valve-seat 6. (Illustrated in Fig. 4.) The valve-seat 6 is also preferably made of glass and is cylindrical in external form 40 in its lower portion, around which is provided the annular bead 5, as stated, from which portion it extends upwardly in form of a conic segment. Lengthwise or through the middle of the valve-seat 6 is provided the opening or

passage-way 7, which is enlarged or flared at 50 each end to allow free flow of the fluid or liquid in emptying the bottle.

In bringing the two halves of the case 1 together the valve-seat 6 is placed between them, the bead 5 entering the groove 4, as 55 shown in Figs. 1 and 2. If desired, these parts may all be made in one piece and of any other suitable material than of glass; but for convenience in construction and for durability I prefer to make them as described. 60

Within the case 1 and extending upwardly from the cavity 2 is the recess or cavity 8, which is preferably circular in section, except that it is enlarged along two opposite sides by the grooves 9. The grooves 9 are 65 extended outwardly at their lower ends along the shoulder 10, formed by the junction of the cavity 8 with the cavity 2, to the outer face of the latter cavity, as shown in Figs. 2 and 3. The grooves 9 are also extended upwardly and inwardly from the upper end of the cavity 8 and coming together merge with the passage-ways 11 at their entrance to the upper end of the cavity 8, as shown in Figs. 1, 2, and 3. The passage-ways 11 begin together in the middle of the upper end of the cavity 8 and separating extend upwardly and outwardly to the top of the case 1 and on opposite sides thereof, as shown in Figs. 1 and 3.

The valve 12 (illustrated in Fig. 5) is preferably made of hard rubber or of such other suitable material as will float on the fluid or liquid with which the bottle is filled and is cylindrical in its outer form and of a diameter to fit neatly the constricted part of the cavity 2. The valve 12 has a recess or cavity 13 within its lower part formed to fit neatly over the conic segment portion of the valve-seat 6, as shown in Fig. 1. The stem 14 projects upwardly from the middle of the top of the valve 12 and is shaped to fit neatly but loosely in the cavity 8, so as to form a guide without binding for the valve 12 in its movements. Within the stem 14 and extending therethrough into the body of the valve 12, but 90 not connecting with the cavity 13, is formed the cavity 15, and from the top of the valve 12 around the base of the stem 14 is formed

the circular groove or cavity 16, which extends down into the body of the valve 12, as shown in Figs. 1, 2, and 5.

The neck of the bottle is of shape and size suitable to conform with and receive the stopper and hold the same a short distance below its mouth and may be reamed out with an emery bur or by other means if necessary to make a close fit.

10 In use the valve 12 is placed over the seat 6, and the two halves of the case 1 are brought together, with the bead 5 of the valve-seat in the groove 4 and the stem 14 of the valve in the cavity 8. The bottle being filled, the 15 stopper is inserted in its neck and rammed home with sufficient force to prevent its being extracted, after which an ordinary cork 18 is used to close the mouth of the bottle, and the package is ready for storage or for the 20 market.

When it is desired to empty or pour from the bottle, the cork 18 is removed and the bottle tilted or inverted, as shown in Fig. 2. The liquid passes out through the passage 7 in the valve seat 6, and filling the cavity 13 of the valve 12 forces the same away from the seat 6, leaving the space 19 therearound, through which the liquid flows into the larger part of the cavity 2 and around the outside 25 of the valve 12. The outer end of the valve 12 being held against the shoulder 10 by the weight of the liquid in the cavity 13, as well as by the flow from the bottle into the same, the liquid passes through the grooves 9 around the end of the valve 12, along the sides 30 of the stem 14, and into the merged inner ends of the passages 11, thence through the same to their outer ends and to the mouth of the bottle, the course of the flow as described 35 being shown by small arrows in Fig. 2.

If an effort be made to refill the bottle with its mouth upward, or substantially so, the flow of the liquid inward through the passages 11 will converge at the top of the cavity 8 and first flow into and fill the cavity 15 in the stem 14. Should any liquid pass around said stem through the grooves 9, the same will flow into and fill the cavity 16 in the valve 12. The weight of the fluid in these cavities

will bring the valve down onto its seat, if it is not already there of its own weight, with its lower outer edge completely filling the cavity 2 in its constricted part below the shoulder 3, as shown in Fig. 1, thus closing all avenue of ingress to the bottle.

55 If an effort be made to refill the bottle with its mouth down, or substantially so, the flow of liquid against the outer ends of the stem 14 and the valve 12 and into the cavities 15 and 16, respectively, therein will force the 60 valve against its seat, if it is not already there by floating, which floating action will be materially assisted by the air which will be caught in said cavities 15 and 16, with the effect, as above, of closing all avenue of ingress to the bottle.

Having described my invention, what I claim as new, and desire to secure by Letters Patent, is—

The combination of a bottle or package 70 having a neck; a case formed in two similar parts or halves located therein, the lower or inner end of said case provided with a cavity somewhat constricted at its lower end, a groove located in said constricted part; a 75 cavity of reduced size located above said larger cavity, with the grooves 9 located at the sides thereof; the passage-ways 11 joined at their inner ends and diverging outward; a valve-seat provided with a passage-way flared 80 at each end thereof, and with a rib to engage said groove; a buoyant valve slidably mounted in the case and provided with a recess or cavity at its lower end to engage the fixed valve-seat, with a groove extending downward and located around the lower portion of the cavity 15 formed in the valve, said groove and cavity closed at their lower ends, and the upward-projecting stem located upon the valve; all arranged substantially as and for 90 the purpose specified.

In testimony whereof I have signed my name to this specification in presence of two subscribing witnesses.

JONAS M. HARMONY.
